Laboratories, Inc., Chicago, Ill., a corporation of
Delaware

Application May 4, 1938, Serial No. 206,008

30 Claims. (Cl. 179—27)

The present invention relates to improvements in telephone systems and has for one of its objects the provision of improved apparatus for terminating multi-party subscribers' lines in a telephone exchange which utilizes automatic switching equipment for setting up connections between the various lines of the system.

In the usual arrangement of existing installed automatic exchanges, wherein certain of the lines extending to the exchange are of the rural multi-party type and others are of the single party type, no differentiation is made between the lines as regards the method of terminating the lines in the automatic switching equipment. As a result, the initiation of a reverting call on one of the rural lines usually results in the seizure of certain of the regular automatic switching equipment provided in the terminating exchange. More particularly, when a reverting call is initiated on a multi-party line, one of the non-numerical automatic switches provided in the exchange is assigned to the use of the line having the calling condition thereon and operates to switch the calling line through to one of the numerical impulse responsive switches. In certain instances, the seized switches are held operated for the duration of the reverting call. In other systems, apparatus is provided for causing the release of the operated switches after a predetermined time interval has elapsed following the seizure of the switches. In either case, certain of the regular automatic switching equipment is tied up so that it can not be used by the other lines.

In applicants' copending application Serial No. 35 196,136, filed March 16, 1938, there is disclosed an improved arrangement for preventing any of the regular automatic switching equipment of the automatic exchange from being taken for use or held out of service when the multi-party lines extending to the exchange are occupied with reverting calls. In brief, the apparatus provided for this purpose comprises a plurality of test links or repeaters at which the multi-party lines terminate, and common equipment including an allotter or link distributor for assigning individual ones of the links to the use of successive calling ones of the multi-party lines. Each test link has embodied therein an impulse responsive switch which responds to a predetermined series of impulses transmitted thereto by way of a calling one of the multi-party lines and functions to switch the calling line through to one of the non-numerical switches forming a part of the automatic switching equipment in the exchange. On

calls routed by way of the automatic switching equipment to the multi-party lines, the selective signaling of the substations on the called lines is accomplished by utilizing code ringing and, more particularly, by equipping the connector switches having access to the lines with impulse responsive code selecting apparatus operative to select the ringing codes corresponding to the particular substations desired. While this arrangement is perfectly satisfactory in operation and is unquestionably the most economical arrangement possible when any substantial number of multi-party lines are to be served, it is somewhat expensive when only a very few lines of the multi-party type are terminated in the automatic exchange. This is true for the reason that common equipment including a test link distributor or allotter must be provided and for the further reason that all of the connector switches having access to the lines must be equipped for selective code ringing.

It is a further object of the present invention, therefore, to provide, in an automatic telephone system including multi-party subscribers' lines, improved apparatus individual to the multi-party subscribers' lines for preventing any of the regular automatic switching equipment from being taken for use by a line having access to the equipment when a reverting call is initiated thereon.

It is an additional object to provide, in improved multi-party line terminating equipment of the character described, apparatus for automatically projecting ringing current over the associated line in response to the seizure thereof by one of the numerical switches, thereby to eliminate this function from the numerical switch or switches having access thereto.

It is a still further object of the invention to provide, in association with a line of the multi-party type and terminating in automatic switching equipment, an improved arrangement for maintaining the line marked as busy when it is occupied with a reverting call.

More particularly, it is an object of the invention to provide, in association with a line of the multi-party type and terminating in automatic switching equipment, improved line busying apparatus which operates when a call is initiated on the associated line, which functions to maintain the line marked as busy independently of its idle or busy condition, and which functions to test the line at spaced intervals and to remove the busy marking when a test indicates that the line is idle.

It is another object of the invention to provide, in association with a subscribers' line of the multi-party type and terminating in the automatic switching equipment in an automatic exchange, improved apparatus so arranged that certain of the substations associated with the line may be equipped for full automatic service and others of the substations may be equipped for manual service only.

10 Two embodiments of the invention are illustrated and described in detail hereinafter. In each embodiment, the multi-party lines are of the ground return type and each thereof extends between an automatic exchange and a manual office. At the manual office, the lines individually terminate in the apparatus provided at a manual operator's telephone station, whereas, in the automatic exchange, the lines are individually terminated at a group of numerical switches by way of which connections are routed from the single party lines of the system to the multi-party lines. Also, in the automatic exchange, the multi-party lines are individually terminated in test links or repeaters which are operative to render the regular automatic switching equipment provided in the exchange accessible thereto. More particularly, each multi-party line extends to a test link or repeater which is connected by way of a trunk line to a non-numerical switch located in the exchange. Individually provided at the respective substations associated with the respective multi-party lines are manually operable magneto generators which are used for signaling between the substations of the lines on reverting calls. In each of the embodiments of the invention there is provided, in each of the test links or repeaters, an automatic switch which responds to a predetermined series of impulses transmitted by way of the associated line, or, in other words, to a predetermined operation of the impulsing device provided at the calling substation associated with the calling line, to switch the line through to an associated one of the non-numerical switches. Also, in each embodiment of the invention, the arrangement of the apparatus is such that a call initiated on one of the single party lines and intended for a substation on one of the multi-party lines may be extended through a portion of the automatic switching equipment provided in the automatic exchange and routed over the called multi-party line to the operator's telephone station in the distant manual office. Through the intervention of the operator, the desired substation on the called line may be signaled by projecting ringing current from the generator provided at this station back over the called line to the ringing device at the desired substation. Also, in each embodiment of the invention, a call initiated at one of the substations on a multi-party line and intended for a substation on one of the single party lines terminating at the automatic exchange may be routed over the calling multi-party line to the operator's station in the distant manual office and then routed from this station back over the multi-party line and through a portion of the automatic switching equipment to the line desired by the calling party. In one embodiment of the invention, it is further contemplated that reverting calls shall be completed only through the intervention of the operator in the manual office, a call first being routed to the operator's telephone station, after which the desired substation on the calling line is signaled from this station by projecting ringing current back over the calling line

to the desired called substation. In the other embodiment of the invention, it is contemplated that reverting calls initiated on the multi-party lines shall be completed without the intervention of an operator, suitable provisions being made in the test links or repeaters individually terminating the multi-party lines for marking the lines as busy when occupied with reverting calls. More particularly, in this modified arrangement, each of the test links is provided with line busying apparatus which operates in response to the initiation of a call on the line and which functions to maintain the associated line marked as busy in the numerical switches to which it extends independently of its idle or busy condition. This apparatus functions automatically to test the associated line to determine its idle or busy condition, to maintain the line marked as busy so long as a busy condition prevails, and to remove the busy marking when a test indicates that the line is idle.

As indicated above, code ringing is utilized for selectively signaling the substations on the multi-party lines. In one modification of the system, such code ringing is under the control of the operator in the manual office. In the second modification of the system, however, it is contemplated that the intervention of the operator on calls to be extended to the substations on the multi-party lines shall not be required, each of the test links or repeaters being equipped with an impulse responsive code selecting switch which is arranged to respond to a code selecting digit dialed at any calling substation and functions to select the particular code corresponding to the desired called substation on the selected called line. The provision of these code selecting switches in the repeaters eliminates the necessity of providing connector switches with special code selecting apparatus.

Further features of the invention pertain to the particular arrangement of the circuit elements whereby the above-outlined objects of the invention are realized.

The novel features believed to be characteristic of the invention are set forth with particularity in the appended claims. The invention, both as to its organization and method of operation, together with further objects and advantages thereof, will best be understood by reference to the specification taken in connection with the accompanying drawings in which Figures 1 and 2 illustrate one embodiment of an automatic telephone system having incorporated therein certain features of the invention as briefly outlined above, and Figs. 3 and 4 illustrate a modified system arrangement having incorporated therein additional features of the invention as outlined above.

Referring now to Figs. 1 and 2 of the drawings, the telephone system there illustrated comprises an automatic exchange, as shown in Fig. 1 and the right portion of Fig. 2; a manual office 200 illustrated in Fig. 2; a plurality of single party lines, one of which is illustrated at 101, extending to the automatic exchange; a multi-party rural line 245 of the ground return type extending between the manual office and the automatic exchange; an operator's telephone station in the manual office; and a plurality of subscriber-controlled automatic switches including the line switches 100 and 115, two selector switches 105 and 120, and two connector switches 110 and 125, for setting up connections between the various subscribers' lines. Although a single multi-

party rural line 245 is shown, it will be understood that additional lines of this character, and having associated therewith equipment identical in form with that illustrated, may be provided. The equipment associated with the line 245 comprises a test link or repeater which is illustrated in detail in the right portion of Fig. 2 and in Fig. 1 and is described in detail hereinafter. Associated with the line 245 are a plurality of substations of the local battery type, two of which are indicated at A and B. The equipment respectively provided at these substations may be of any desired commercial construction which comprises a telephone transmitter and receiver, a cradle or hook switch, a ringer, and a manually operable magneto generator for projecting ringing current over the associated line. Each of the substations associated with the single party lines, such, for example, as the substation 20 C associated with the line 101, may likewise be of any desired well-known construction and preferably comprises the usual hand set type of transmitter and receiver, a cradle or hook switch, a ringer, and an impulsing device for transmitting the switch control impulses by way of the associated line to the automatic switching equipment located in the terminating exchange. The modified arrangement illustrated in Figs. 3 and 4 is, in general, substantially the same as that illustrated in Figs. 1 and 2. In brief, the system illustrated in Figs. 3 and 4 comprises an automatic exchange; a manual office 480; a plurality of single party subscribers' lines, one of which is indicated at 301 extending to the automatic exchange; a multi-party rural line 486 of the ground return type extending between the manual office 480 and the automatic exchange; and a plurality of subscriber-controlled automatic switches, including two line switches 300 and 400, two selector switches 305 and 405, and two connector switches 310 and 410, for setting up connections between the various lines of the system. The end of each single party subscriber's line remote from the automatic exchange terminates in a substation equipped for full automatic service, that associated with the line 301 being diagrammatically illustrated at E and comprising substation equipment which may be identical with that provided at the substation 50 C, for example. The multi-party line 486 terminates in a repeater comprising the circuit elements illustrated in detail in Figs. 3 and 4. Associated with this line are a plurality of substations, certain of which are equipped for full automatic service and others of which are arranged for manual service only. More particularly, with the system illustrated, the substation A' is equipped for manual service, the arrangement being such that only reverting calls, or calls to the manual office 480, may be successfully completed without the intervention of an operator in the manual office. The substation B', on the other hand, is equipped for full automatic service, the equipment provided at this substation 60 including, in addition to the usual magneto generator, ringer, and telephone hand set, an impulsing device so arranged that calls to the automatic subscribers' lines may be completed in the usual manner and without the intervention of an operator in the exchange 480, by dialing the regular directory number of the desired automatic subscriber's line or substation.

It is pointed out generally with reference to each of the two modifications briefly described above that the line switches 100, 115, 300 and 400 and the other similar switches corresponding thereto are non-numerical switches in the sense that they are ineffective to perform any line selecting functions other than that of automatically selecting idle ones of the selector switches. 5 The selector and connector switches, on the other hand, are commonly known as numerical switches in that they are individually operative to perform line selecting functions in response to impulses transmitted thereto. It will be understood that, in each of the two systems illustrated, a plurality of switches of each type, namely, a plurality of line switches, a plurality of selector switches, and a plurality of connector switches, are provided in the system for performing the usual line switching functions. The numerical switches of each type are respectively arranged in groups and, in accordance with universally followed practice, the number of switches in each group is determined by the maximum volume of traffic the particular switch group is required to handle. Further in accordance with conventional practice, each of the single party subscribers' lines is multiplied to the corresponding bank contacts of a group of connector switches, whereby a plurality of switches are available for setting up connections between each line and any other line of the system. The line switches, on the other hand, are individually associated with the respective subscribers' lines, that terminating the line 101 being indicated at 100 and that terminating the line 301 being indicated at 300. Each of the line switches 100, 115, 300, 400, etc., is preferably of the well-known rotary type, of which there are several commercial embodiments. Each of the selector and connector switches, on the other hand, is preferably of the well-known Strowger type having embodied therein a Strowger switching mechanism including a plurality of bank contacts arranged in levels; a wiper carriage structure adapted to be translated vertically to bring the wipers thereof to a position opposite a particular level of bank contacts and then rotated to bring the wipers into engagement with a particular set of contacts in a selected level; vertical, rotary, and release magnets; and relays suitably connected and arranged to control the energization of the various magnets and the line switching in accordance with the particular functions of the particular switch. Obviously, the particular arrangement of the control apparatus embodied in the switches of different type is different in each instance depending upon the character of the switch.

Neglecting for the present the details of the apparatus terminating the multi-party subscribers' lines and considering generally the operation of the system illustrated in Figs. 1 and 2, for example, when a subscriber, such, for example, as the subscriber at the telephone station C, initiates a call over the line 101 to a second automatic subscriber's telephone by lifting his receiver from its hook, a loop circuit is completed by way of the line 101 for initiating the operation of the line switch 100 to select a trunk line leading to an idle selector switch. Assuming, for example, that the selector switch 105 is the first numerical switch selected by the line switch 100 for the use of the calling line 101, when the trunk line leading to this selector switch is found, the loop circuit is extended thereto and the selector switch is conditioned to respond to the first series of impulses dialed at the calling substation. With the selec-

tor switch 105 in this condition, dial tone is returned over the established loop to the calling subscriber to indicate that the dialing operation may be started. When the first digit is dialed at 5 the calling substation, the switch 105 elevates its wipers to a position opposite the level of bank contacts terminating the trunk lines respectively extending to the connector switches having access to the called line. Following this operation, 10 the wipers of the switch 105 are automatically stepped over the contacts of the selected level until the trunk line leading to an idle connector switch of the selected group is found. Assuming, for example, that the connector switch 110 is the 15 first idle connector switch available, when the wipers of the switch 105 are stepped into engagement with the contacts terminating the trunk line extending to this connector switch, the subscriber's loop circuit is extended thereto, 20 thereby to cause the connector switch 110 to be conditioned to respond to the second and third series of impulses dialed at the calling substation. In response to the dialing of the second digit, the wipers of the connector switch 110 are 25 stepped vertically to a position opposite the level of bank contacts at which are terminated the lines of the ten-line subgroup including the called line. Following this series of impulses, the connector switch is conditioned to rotate its wipers 30 step by step in accordance with the impulses making up the third and final digit dialed at the calling substation. When this final digit is dialed, the wipers of the switch 110 are stepped into engagement with the set of bank contacts terminating 35 the called line. In accordance with conventional practice, suitable provisions are made in the connector switch 110 for testing the called line to determine its idle or busy condition, for returning busy tone over the established loop to 40 the calling subscriber in case the called line is busy, and for applying ringing current to the called line in the event this line is idle at the time it is selected. Assuming the called line is idle, the desired conversational connection is completed 45 when the call is answered at the called substation. Also, in accordance with conventional practice, the apparatus is arranged to insure its release when the connection is cleared out at the calling and called substations. To 50 this end, the control apparatus embodied in the connector switch 110 is so arranged that the release of the connection is entirely under the control of the calling party.

The mode of operation of the automatic switching equipment diagrammatically illustrated in 55 Figs. 3 and 4 to establish a connection between two single party automatic subscribers' lines is substantially identical with that just described with reference to the apparatus illustrated in Fig. 60 1. For this reason, and in the interests of brevity, it is deemed unnecessary to comment generally on the operation of the apparatus illustrated in Figs. 3 and 4.

Referring now more particularly to the apparatus 65 provided in association with the multi-party line 245, and considering first the repeater or test link as illustrated in Figs. 1 and 2, this repeater comprises a repeating coil 180, a line or impulse responsive relay R150, a slow-to-release hold relay 70 R140, and a switching-through relay R130 which is under the control of an impulse responsive switch 170. The repeater terminates one end of a trunk line 135 which extends to the non-numerical line switch 115 and to the bank contacts of 75 the connector switches in the group including

the switch 110. The switch 110 is preferably of the well-known minor type and comprises a single set of bank contacts 171, a wiper 172, an operating magnet 173 for driving the wiper 172 over the contacts of the set 171, a release magnet 174, and off-normal springs 175 for controlling the energization of the release magnet. Also included in the test link or repeater are two relays R240 and R250, the second of which is arranged to respond to the application of ground potential to the control conductor C104 of the line 245 and functions to project ringing current out over the associated line 245. This ringing current is derived from a ringing current generator schematically indicated at 210. The relay R240 functions to disconnect 10 the ringing current generator from the line 245 a short time interval after the relay R250 functions to connect the ringing current generator thereto. More particularly, the relay R250 is provided with a vibrating reed type of armature RA255 which is 15 weighted at one end thereof in a well-known manner so that, when R250 operates to move RA255 into engagement with RA255, the last-mentioned weighted armature vibrates for an interval to prevent the relay R240 from being sufficiently 20 energized to operate. Also included in the repeater is an additional relay R160 which is of the polarized type, this relay being provided to control the energization of a signal device located at the operator's telephone station in the remote 25 manual office in the manner described in detail hereinafter. Specifically, the relay R160 is so arranged that it is operative from one of its two positions to the other when the polarity of the current flowing through the two repeater windings 30 183 and 184 and over the conductors of the trunk line 135 to certain of the non-numerical and numerical switches provided in the automatic exchange is reversed.

The apparatus provided at the operator's station 40 in the distant manual office, wherein the line 245 is terminated, comprises a repeating coil 225, an answer jack 218, a ringing key 205, a dialing key 210, a drop or signal device 233, an impulsive device 221, a disconnect supervisory 45 lamp 232, and a relay R230 for controlling the lamp 232, all connected and arranged in the manner illustrated and operative in the manner pointed out in detail hereinafter. It is mentioned here that the relay R230 which controls 50 the energization of the signal lamp 232 is connected and arranged to be energized in series with the line relay R150 provided in the automatic exchange over a circuit including the line 55 245. The relay R230 is of the marginal type such that it is only sufficiently energized to operate when the resistor 162 is excluded from its operating circuit.

Referring now more particularly to the operation of the apparatus to extend a connection 60 from one of the regular automatic subscribers' lines, such, for example, as the line 101, to one of the substations associated with the line 245, and assuming that the line switch 100 operates to extend the connection from the calling substation C to the selector switch 105, when a predetermined digit is dialed at this substation, the selector switch noted is caused to operate automatically to select an idle one of the connector switches in the group including the switch 110. 70 Assuming that the last-mentioned switch is the first available idle switch of the selected group, when the calling subscriber's loop circuit is extended thereto, the control apparatus embodied therein operates to condition the switch to re- 75

spond to the impulses of the second digit dialed at the calling substation. When the second digit is dialed, the connector switch 110 operates in a well-known manner to select a group of ten lines including the called line 245. When the third digit is dialed at the calling substation, this connector switch further operates to select the particular called line 245 from the selected group of lines. As pointed out more in detail herein-after, if the selected line 245 is busy, ground potential is present on the control conductor C104 thereof so that the connector switch, upon testing the condition of the line and finding the line busy, operates to return busy tone to the calling subscriber to indicate that the desired connection can not immediately be established. If, on the other hand, the selected called line is idle, battery potential as extended through the winding of R250 and by way of C103, RC142, and RA141 is applied to the control conductor C104. With the line idle, the connector switch 110 operates to extend the calling subscriber's loop circuit through to the repeater 180, thereby to energize the polarized relay R160. Simultaneously with the switching-through operation, ground is applied to C104 in the connector switch to complete a circuit for energizing the relay R250, this circuit extending from ground on the control conductor noted by way of RA141, RC142, C103 and the winding of R250 to battery. Upon operating, the relay R250 completes a holding circuit for itself, this circuit extending from ground as applied to C104 by way of RA256 and the winding of R250 to battery. At RA251 and RC253, the relay R250 completes a circuit for energizing the signal device or drop 233 provided in the distant manual office, this circuit extending from the ungrounded terminal of the ringing current generator 270 by way of RC242, RA241, RC253, RA251, the conductor 245, the switch springs 216 and 218, the winding of the drop 233 and the condenser 234 to the grounded terminal of the ringing current generator. Through the operation of its armature RA254, the relay R250 starts the weighted armature RA255 vibrating. After an interval required for the amplitude of vibration of RA255 to die down, this armature settles into engagement with RA254 to complete an obvious circuit for energizing the relay R240. Upon operating, the relay R240 interrupts, at RA241 and RC242, a point in the above-traced circuit for conducting ringing current over the line 245 to the operator's position in the distant manual office. At RA241 and RC243, the relay R240, upon operating, prepares a point in the talking circuit to be completed between the calling subscriber's substation and the operator's telephone station.

The polarized relay R160 operates when energized over the calling subscriber's loop circuit to interrupt, at RA161, the path normally short-circuiting the resistor 162. Following the operation of the three relays R160, R250 and R240, no further operation of the apparatus occurs until the call, as extended to the manual office, is answered at the operator's telephone station. The operator answers the call in the usual manner by inserting the plug terminating her head set, not shown, into the answer jack 215. When this operation is performed, a further point is opened, at the springs 216 and 218, in the above-traced circuit for energizing the drop 233. At the springs 216 and 217, a circuit is completed for energizing R230 in series with R150, this circuit extending from ground at the lower terminal of the repeater winding 228 by way of this winding, the winding of R230, the switch springs 213 and 212, the switch springs 208 and 206, the springs 217 and 216, the conductor 245, RA251, RC253, RA241, RC243, C102, the repeater winding 181, the resistor 162, and the winding of R150 to battery. Due to the inclusion of the resistor 162 in this circuit, the relay R230 is not sufficiently energized to operate when the circuit is completed. The relay R150, however, is sufficiently energized to operate and, upon operating, completes, at RA151 and RC153, an obvious circuit for energizing the slow-to-release hold relay R140. When the last-mentioned relay operates, it interrupts, at RA141 and RC142, a point in the above-traced operating circuit for R250 and applies, at RA141 and RC143, multiple ground to the control conductor C104, thereby to complete a multiple holding circuit for R250. At RA144 and RC145, the relay R140 opens a point in the circuit, traced hereinafter, for energizing the release magnet 174 and, at RA144 and RC146, it prepares a point in the circuit, traced hereinafter, for energizing the operating magnet 173 of the switch 170, this latter circuit now being held open at the operated armature RA151 of the relay R150.

When the operator answers the call, a talking circuit is completed between her telephone and the calling subscriber's substation, which circuit will be apparent from an inspection of the drawings. It is pointed out, however, that this circuit includes a link interconnecting the automatic exchange with the manual office and comprising the ground return line 245. Specifically, this link extends from ground at the lower terminal of the repeater winding 228 by way of this winding, the condenser 235, the switch springs 213, 212, 208, 206, 217 and 216, the line conductor 245, RA251, RC253, RA241, RC243, C102, the repeater winding 181, the condenser 185 and the repeater winding 182 to ground.

Upon conversing with the calling party to ascertain which of the rural substations is desired, the operator in the manual office 200 may proceed to ring the desired substation by operating the ringing key 205 in accordance with the particular code corresponding to the called substation. Each time the key 205 is operated to its off-normal position, the springs 206 and 208 are opened to prevent ringing current from being projected through the winding 228 of the repeater 225 and the springs 206 and 207 are closed to project ringing current out over the line 245. Assuming that the substation A is being called, the key 205 is actuated in accordance with the coded signal identifying this substation. The path which the ringing current traverses in energizing the ringer or signal device at the substation A extends from the ungrounded terminal of the ringing generator, not shown, by way of the springs 207, 206, 217, and 216, the line 245, the condenser 236 and the ringer at the called substation to the grounded terminal of the ringing current generator. A portion of this current is also conducted through the ringing devices at the other substations associated with the line 245, but, due to the coded nature of this current, the subscriber at the called substation is informed that his substation is being called to the exclusion of the other substations. During each period when ringing current is being projected over the line 245, the line relay R150 is held energized over a circuit slightly different from its operating

circuit as traced above. Specifically, this holding circuit for R150 extends from the grounded terminal of the ringing generator, not shown, by way of this generator, the switch springs 207, 5 206, 217 and 218, the line conductor 245, RA251, RC253, RA241, RC243, C102, the repeater winding 181, the resistor 162 and the winding of R150 to battery. Obviously, at the end of each ringing period, the operating circuit, as traced previously, is recompleted through the closure of the 10 springs 206 and 208.

When the call is answered at the called 15 substation A, the desired talking connection is fully completed between the calling and called substations. The operator does not remove the answer plug from the jack 215 until after the conversation is terminated. If, at the end of the 20 conversation, the calling subscriber at the substation C is the first to hang up, the operated switch train comprising the connector switch 110, the selector switch 105 and the line switch 100 is released in the manner set forth above. When 25 the calling party hangs up the polarity of the current traversing the winding of R160 is reversed, causing this relay to restore to short-circuit, at RA161, the resistor 162. As a result, the resistance of the circuit including the serially connected windings of R230 and R150 is lowered 30 and the current traversing the winding of R230 is increased sufficiently to cause this relay to operate. Upon operating, the relay R230 completes, at RA231, an obvious circuit for energizing 35 the signal lamp 232, thereby to indicate to the operator that the line 245 is no longer occupied with a call. The operator may now release the line for further use by removing the answer plug from the jack 215, thereby to interrupt, at 40 the springs 216 and 217, the circuit over which the windings of R230 and R150 are energized in series. When this circuit is interrupted, the relay R230 restores to open the circuit for energizing the lamp 232, and the relay R150 restores to open, at RA151 and RC153, the operating circuit 45 for R140. At RA151 and RC152, the relay R150, upon restoring, completes the above-mentioned circuit for energizing the operating magnet 173, this circuit extending from ground at the lower terminal of the repeater winding 182 by way of 50 RA151, RC152, RA144, RC146, RA131 and the winding of the magnet 173 to battery. The relay R140 restores, after an interval, to interrupt, at RA141 and RC143, the holding circuit for R250 55 and to remove ground from the control conductor C104, thereby to mark the line 245 as idle in the bank contacts of the connector switches to which the trunk line 135 extends. At RA144 and RC146, the relay R140 interrupts the above-traced 60 circuit for energizing the magnet 173, causing this magnet to be deenergized. As a consequence of the energization and deenergization of the magnet 173, the wiper 172 is stepped one step and the off-normal springs 175 are closed. When the 65 springs 175 are closed a circuit is completed for energizing the release magnet 174, this circuit extending from ground at the lower terminal of the repeater winding 182 by way of RA151, RC152, RA144, RC145, the off-normal springs 175 and the winding of the magnet 174 to battery. When 70 energized over this circuit, the magnet 174 attracts its associated armature, not shown, to cause the wiper 172 to be returned to its home position. When this occurs, the off-normal 75

springs 175 are opened to interrupt the circuit for energizing the magnet 174.

When R250 restores, it opens, at RA251 and 5 RC253, a point in the above-traced circuit for energizing the drop 233 and interrupts, at RA254 and RA255, the operating circuit for R240. The relay R240, upon restoring reprepares, at RA241 and RC242, a point in the circuit for energizing the drop 233. Following the restoration of R240, the connection is entirely released. 10

Referring now to the operation of the apparatus to set up a connection between the line 245 and one of the automatic subscribers' lines on a call initiated at one of the rural substations, such, for example, as the substation A; when the magneto generator at the last-mentioned substation is operated in the usual manner, ringing current is projected over the line 245 to cause the operation of the drop 233, thereby to indicate to the operator in the manual office 200 that a call 15 on the line 245 awaits her attention. The operator answers the call in the manner pointed out above, that is, by inserting the answer plug terminating her telephone set in the jack 215, thereby completing a talking connection to the 20 calling subscriber's substation. When the call is answered in this manner, a circuit is completed for energizing the relay R150 and the relay R230 in series, this circuit being substantially similar to that traced previously but extending over the 25 line conductor 245 and by way of RA251 and RC252 to C102, rather than by way of RC253, RA241 and RC243. In the present case, the relay R160 is restored and the resistor 162 is short-circuited, so that the current flowing over the circuit noted is of a value sufficient to cause the 30 operation of R230 as well as the operation of R150. When R230 operates, it completes the 35 above-mentioned circuit for energizing the signal lamp 232, and, when R150 operates, it completes the 40 above-mentioned circuit for energizing the slow-to-release relay R140. When R140 operates, it opens, at RA141 and RC142, a point in the operating circuit for R250 and, at RA141 and RC143, applies ground to the control conductor C104, thereby to mark the line 245 as busy 45 in the bank contacts of the connector switches to which the trunk line 135 extends. At RA144 and RC146, the relay R140 prepares a point in the 50 circuit, traced above, for energizing the operating magnet 173.

Upon ascertaining the number of the substation desired by the calling party, the operator may actuate the dial key 210 to the off-normal position to connect the impulsive device 221 in 55 circuit with the line relay R150. More particularly, when this key is operated to its off-normal position, the previously traced circuit for energizing R230 is interrupted at the springs 212 and 213, and an alternative circuit extending 60 from ground at the lower impulsive spring of the device 221 and substantially similar to that traced above is completed at the springs 211 and 212 for holding R150 energized. Following the 65 operation of the key 210 to its off-normal position, the operator may actuate the dial controlled impulsive device 221 in accordance with the directory number of the desired subscriber's substation.

As pointed out in the introductory portion 70 of the specification, it is necessary to dial a prefix digit at the operator's telephone station before the calling line is switched through to cause the line switch 115 to operate. With the arrangement illustrated, a prefix digit comprising 75

ing ten impulses is required. At the beginning of the first impulse of this digit, the circuit over which the line relay R150 is being held energized is interrupted at the springs of the impulsive device 221 and the line relay restores to complete, at RA151 and RC152, the above-traced circuit for energizing the operating magnet 173 of the switch 170. Upon being energized over the above-traced circuit, the magnet 173 attracts its associated armature, not shown, to condition the associated ratchet and pawl mechanism to step the wiper 172 one step or into engagement with the first contact of the set 171. When, at the end of the first open circuit pulse, the impulsive springs of the device 221 are closed to complete the circuit for energizing the line relay R150, the last-mentioned relay operates to interrupt the above-traced circuit for energizing the magnet 173. Upon being deenergized, the magnet 173, in cooperation with its associated ratchet and pawl mechanism, steps the wiper 172 one step or into engagement with its associated first contact. When the wiper 172 takes this first step, the off-normal springs 175 are closed to 25 prepare the circuit, traced above, for energizing the release magnet 174. During each succeeding impulse occasioned by further operation of the impulsive device 221, the wiper 172 of the switch 170 is caused to advance one step, in a manner identical with that just described. At the end of the ten impulses comprising the prefix digit, the wiper 172 is, therefore, advanced into engagement with its associated tenth contact, assuming the impulsive conditions of the line are 30 such that the line relay R150 responds to the impulses in a satisfactory manner.

Immediately the wiper 172 is advanced into engagement with the tenth contact of the set 171, an obvious circuit is completed for energizing R130. When R130 operates, it interrupts, at RA131, a point in the above-traced circuit for energizing the magnet 173, thereby to prevent the switch 170 from responding to any further impulses dialed at the operator's station. At its armatures RA132 and RA133, the relay R130 completes a loop circuit for initiating the operation of the line switch 115 to select an idle one of the selector switches. The last-mentioned circuit may be traced from the lower terminal 35 of the repeater winding 184 by way of the winding of R160, the repeater winding 183, RA133, one side of the trunk line 135, the windings of the line relay in the line switch 115 connected in series with battery, the opposite side of the trunk line 135, RA132 and RA134, back to the lower terminal of the repeater winding 184. The polarity of the current flowing in this loop circuit, which current is supplied by the battery connected in series with the two windings of the line relay, conventionally provided in the line switch 115, is such that the polarized relay R160 does not operate.

When the above-mentioned loop circuit is completed, the line switch 115 operates to select a 40 trunk leading to an idle selector switch. Assuming, for example, that the selector switch 120 is the first available idle switch, the line switch 115 functions to switch the above-traced loop circuit through to the selector switch 120, thereby to cause this switch to be conditioned to respond to the second series of impulses dialed at the operator's station, and dial tone to be returned over the established loop to the operator. The line relay R150 follows the impulses of the 45 second digit in the same manner as is pointed

out above with reference to the operation of the apparatus during the dialing of the prefix digit and, at its armature RA154, it repeats the impulses to the selected selector switch 120. The last-mentioned switch responds in the usual manner by operating its wipers to a position opposite the level of bank contacts terminating the trunks leading to the group of connector switches having access to the called line. If it be assumed, for example, that the substation C is the particular substation desired by the calling substation, the selector switch will respond to the impulses of the second digit to select the group of trunks respectively extending to the connector switches in the group including the switch 125. 50 Following the dialing of the second digit, the selector switch 120 automatically operates, in a well-known manner, to select the first available idle switch which, in the present case, may be assumed to be the switch 125. When this connector switch is selected, the above-mentioned loop circuit is switched through to cause the switch to be conditioned to respond to the impulses of the third and fourth digits dialed at the operator's station. The connector switch noted, 55 namely, the switch 125, responds to the impulses of the third and fourth digits by first selecting the group of ten lines including the called line 101 and then selecting the particular called line of the selected group in a well-known manner. The connector switch 125 also operates to test the condition of the called line, to return busy tone over the loop to the operator's telephone in the event the called line is busy, and to apply 60 ringing current to the called line in the event this line is idle.

Following the completion of the dialing operation, the operator at the manual office 200 restores the dial key 210 to its normal position to 65 recomplete the previously traced circuit for energizing R230 in series with the line relay R150. When this operation is performed, and if the called line is busy, the operator will receive busy tone and will thus be informed that the desired connection can not immediately be established. On the other hand, if the called line is idle, ring-back tone will be received by the operator to indicate that the desired called substation is being rung.

When the call is answered at the called substation C, battery is reversed back over the loop extending to the repeater 180, thereby to reverse the direction of current flow through the winding of the polarized relay R160. As a consequence, the relay R160 operates to interrupt, at 70 RA161, the path short-circuiting the resistor 162, thereby to insert this resistor in the series circuit over which R150 and R230 are being held energized. The resulting decrease in the magnitude of the current in this circuit causes R230 to restore to interrupt, at RA231, the circuit for energizing the signal lamp 232. It will, of course, be understood that, when the call is answered at the called substation, the desired conversational circuit is completed between the calling and 75 called parties. Here again the operator retains the answer plug in the jack 215 until the conversation is terminated.

When the conversation is terminated and the called party hangs up, battery is again reversed 80 over the loop extending back to the repeater 180 to cause the restoration of the polarized relay R160. As a result, R160 restores to short-circuit, at RA161, the resistor 162, thereby to cause the reoperation of the relay R230 and the reenergiza- 85

tion of the signal lamp 232. The energization of this lamp indicates to the operator that the established connection is ready to be released. The release of the connection is effected in a manner similar to that described above. Thus, when the answer plug is removed from the jack 215, the series circuit including the two windings of R150 and R230 is interrupted and these two relays restore. The relay R230, upon restoring, interrupts the circuit for energizing the signal lamp 232, and the relay R150, upon restoring, interrupts at RA154, the loop circuit extending to the line switch 115 and, at RA151, the circuit over which R140 is being held energized. When the relay 10 R140 restores, it completes, at RA144 and RC145, the above-traced circuit for energizing the release magnet 174. The release magnet now attracts its armature, not shown, to cause the wiper 172 to be returned to its normal position. When the 15 wiper 172 is disengaged from its associated tenth contact, the operating circuit for R150 is interrupted and this relay restores to reprepare, at RA131, a point in the circuit for energizing the operating magnet 173 and to interrupt, at its 20 armatures RA132 and RA133, further points in the loop circuit extending to the line switch 115.

When the switch 170 is returned to its normal position, the off-normal springs 175 are opened to interrupt the operating circuit for the release 25 magnet 174. The slow-to-release relay R140, upon restoring, removes ground, at RA141 and RC143, from the control conductor C104, thereby to mark the line 245 as idle in the bank contacts of the connector switches to which the trunk line 135 extends. When the loop circuit extending to the line switch 115 is interrupted, the operated switch train comprising the switches 115, 120 and 125 is released in a manner substantially similar to that pointed out previously. Following 30 the restoration of R130, R140 and R150 and the restoration of the switch 170 to normal, the apparatus is completely released and in readiness for further use.

Although a connection between two substations 35 connected to the line 245 may be performed directly in the conventional manner through the proper actuation of the magneto generator at the calling substation to code ring the desired called substation, such connections are preferably 40 completed with the assistance of the operator in the manual office 200. The advantage of enlisting the operator's assistance in completing a reverting call connection resides in the fact that the operator, by retaining her answer plug in the 45 jack terminating the line, can guard the line against seizure by one of the connector switches in the automatic exchange, whereas the line is unguarded when such a call is directly completed. If, for example, a subscriber at the substation A 50 desires a connection with the substation B, the call is initiated in the manner pointed out above, that is, through the operation of the magneto generator provided at the substation A. The resulting operation of the drop 233 indicates to the 55 operator in the manual office that a call has been initiated on the line 245. The call is answered in the usual manner by inserting the answer plug in the jack 215 to establish a talking connection by way of the line 245 to the calling substation 60 A. When the answer plug is inserted in the jack 215, the above-traced circuit is completed for energizing R150 in series with R230 and, since at this time the polarized relay R160 is restored, both of the relays R150 and R230 operate. When 65 the relay R150 operates, it completes the oper-

ating circuit for R140, which latter relay, upon operating, applies, at RA141 and RC143, ground to the control conductor C104, thereby to mark the line 245 as busy in the bank contacts of the connector switches to which the trunk line 135 extends.

Upon ascertaining the party desired by the calling subscriber, the operator may actuate the ringing key 205 to project ringing current back over the line 245 in the manner described previously. The coded nature of this current indicates to the called subscriber that his substation is being called and informs the parties at the other substations connected to the line that the call is intended for the substation B. Obviously, when the call is answered at the called substation, the desired conversational connection is established between the two substations A and B. Here again, the operator retains the answer plug in the jack 215 for the purpose of holding the relays R140 and R150 operated, thereby to maintain the line 245 guarded against seizure by one of the connector switches provided in the automatic exchange. In this case, it is necessary for the operator to challenge the 25 connection at intervals to determine whether the conversation between the calling and called parties is terminated. This is true for the reason that no means are provided for indicating when the parties at the calling and called substations 30 hang up to clear the line. Upon ascertaining that the conversation is terminated, the operator may release the connection by withdrawing the answer plug from the jack 215, thereby to interrupt the series circuit including the windings of R230 and R150. Upon restoring, R150 35 interrupts the operating circuit for R140 and completes, at RA151 and RC152, the above-traced circuit for energizing the operating magnet 173. Shortly thereafter and when R140 restores, ground is removed from the control conductor C104 to mark the line 245 as idle and the circuit for energizing the magnet 173 is interrupted. As a result of the energization and deenergization 40 of the magnet 173, the wiper 172 of the switch 170 is stepped one step or into engagement with its associated first contact, and the off-normal springs 175 are closed. With the two relays R150 and R140 restored and when the springs 175 are 45 closed, the above-traced circuit for energizing the release magnet 174 is completed. The resulting operation of this magnet causes the switch 170 to be restored to normal and the springs 175 to be opened to interrupt the circuit for energizing the release magnet. Thus, the connection 50 is entirely released and the line 245 is in readiness for use on another call.

From the foregoing description it will be apparent that a connection can only be routed over the line 245 and by way of the automatic switching equipment in the automatic exchange by dialing a predetermined prefix digit at the operator's telephone station. It will also be noted that when a reverting call is initiated on the line 245, the relay R130 is not energized and, hence, 55 none of the regular automatic switching equipment is assigned to the use of the line. If for any reason the manual office operator, in initiating a call to one of the automatic subscribers' substations, fails to dial the required prefix digit 60 of ten impulses, or the impulsing conditions of the line are such as to preclude a faithful response thereto by the line relay R150, the minor switch 170 will not be operated to its tenth off-normal position to cause the operation of R130. 65

in response to the impulses of the prefix digit. Hence, the loop circuit to the line switch 115 will not be completed and none of the regular automatic switching equipment will be assigned to the use of the calling line.

It will further be apparent from the foregoing description that, with the arrangement illustrated in Figs. 1 and 2, the selective signaling of the substations on the line 245 is entirely under the control of the operator in the manual office 200. With the arrangement illustrated in Figs. 3 and 4, on the other hand, provisions are made whereby a calling automatic subscriber, by dialing a ringing digit following the usual line selecting digits, may cause the proper coded ringing current, corresponding to the desired substation, automatically to be projected over the line to signal the desired substation. By virtue of this improved arrangement, the operator's assistance in completing calls originated at an automatic substation on a line terminating in the automatic exchange is not required. However, on calls originating at substations provided on the line extending between the automatic and manual offices which are not equipped for automatic service, the intervention or assistance of the operator in the manual office is necessary in setting up the desired connections.

Referring now more particularly to the apparatus provided in the system illustrated in Figs. 3 and 4 in association with the multi-party line 486, it is pointed out that the equipment located at the operator's telephone station in the manual office 480 may be identical with that described previously with reference to the corresponding equipment provided for terminating the line 245 of the system illustrated in Figs. 1 and 2. The repeater or test link located in the automatic exchange and terminating the other end of the line 486 comprises a repeating coil 315 connected by way of a trunk line 346 to certain of the numerical and non-numerical switches in the automatic exchange; a line or impulsive relay R415; a slow-to-release hold relay R430; an impulse correcting network comprising the three relays R420, R440, and R450, and a switching-through relay R460 which is under the control of an impulse responsive switch 470. The relay R450 is an impulsive relay which responds to the operation of R415 and functions to repeat impulses to the switch 470 and to the automatic switches constituting the regular automatic switching equipment provided in the exchange. The switch 470 is of the well-known minor type and comprises a single set of bank contacts 474, a wiper 475, an operating magnet 471 for driving the wiper 475 over the contacts of the set 474, a release magnet 472, and off-normal springs 473 for controlling the energization of the release magnet. As pointed out in detail hereinafter, the equipment just described, namely, that illustrated in Fig. 4, is the portion of the repeater which operates when a connection is being routed from one of the substations associated with the line 486 or from the operator's telephone station to one of the other lines terminating at the automatic exchange. On calls routed by way of the automatic switching equipment to a substation on the line 486, the apparatus illustrated in Fig. 3 is primarily the apparatus which enables the desired connections to be established. More particularly, the apparatus illustrated in Fig. 3 is provided for controlling the selection of a ringing code corresponding to a desired substation on the line 486. In brief, this apparatus

comprises a switching relay R320, a line relay R325, a slow-to-release hold relay R330, a pair of control relays R335 and R340, a code selecting switch, and a relay network comprising the three relays R365, R370 and R375 connected and arranged to control the application of ringing current to the line 486. Ringing current is derived from a ringing current generator 390 and the voltage developed by this generator is coded by the ringing interrupter 395. The ringing current generator and the ringing interrupter may be of any desired commercial construction, although preferably the ringing interrupter 395 is of the form described and claimed in copending application Serial No. 203,474, Clarence E. Lomax, filed April 22, 1938. This interrupter functions to apply to the five ringing current conductors terminating at the contacts of the code selector switch the voltage developed by the ringing current generator for coded intervals which are different for each of the ringing current conductors. The code selector switch is preferably of the well-known minor type and comprises a single set of bank contacts 381, a wiper 382, an operating magnet 379 for driving the wiper 382 over the contacts of the set 381, a release magnet 378, and off-normal springs 380 for controlling the energization of the control relay R340.

For the purpose of marking the line 486 as busy in the bank contacts of the numerical switches having access thereto when this line is occupied with reverting calls, there is provided a novel and improved arrangement comprising the two relays R350 and R360 and the impulse generator 385. The relay R350 is so constructed that it operates when its upper winding is energized with direct current or with alternating ringing current. The generator 385 may be of any well-known construction which includes means for alternately applying ground pulses to the time pulse leads C303 and C304 at spaced intervals. If desired, it may comprise a commutator driven by a synchronous motor through a gear reduction box and including grounded segments suitably arranged to engage brushes respectively terminating the leads C303 and C304.

Referring now more particularly to the operation of the apparatus illustrated in Figs. 3 and 4 to set up a connection between one of the automatic subscribers' substations, as, for example, the substation E connected to the line 301, and one of the substations connected to the line 486, and assuming that the line switch 300, the selector switch 305 and the connector switch 310 are successively operated in the usual manner to select the called line 486; when the connector switch 310 completes its operation and if the line 486 is idle, ground is applied to the control conductor C482 in the connector switch and the calling subscriber's loop circuit is extended by way of the trunk line 346 to the repeater 315. When ground is applied to C482, a circuit is completed for energizing R320, this circuit extending by way of RA431, RC432, C483, RA351, RC353 and the winding of R320 to battery. Upon operating, the relay R320 short-circuits at RA323 the upper winding of R350, thereby to exclude this winding from the talking circuit ultimately to be established. At RA323, the relay R320 opens a point in the circuit, traced hereinafter, for energizing R415. At RA321 and RA322, the relay R320 completes a circuit for energizing R325, this circuit extending from ground at the lower terminal of the upper winding of R325 by way

of this winding, RA321, the repeater winding 318, one side of the calling loop circuit, the bridge across the conductors of the line 301 at the calling substation, the other side of the calling subscriber's loop circuit, the repeater winding 319, RA322 and the lower winding of R325 to battery. In this regard it is pointed out that the connector switch 310 and the other corresponding switches are arranged to switch through on a call of the character under consideration. When energized over the above-traced circuit, the relay R325 operates to complete, at RA326 and its associated lower contact, an obvious circuit for energizing the slow-to-release hold relay R330. When R330 operates, it applies, at RA331, multiple ground to the control conductor C482; opens, at RA332 and its associated upper contact, a point in the circuit, traced hereinafter, for energizing the release magnet 378; and prepares, at RA332 and its associated lower contact, a circuit for energizing R335 in parallel with the rotary switch operating magnet 379. At RA333, the relay R330 applies ground to the ringing interrupter start conductor C396, thereby to initiate the operation of the interrupter 395. Following the operation of R330, the apparatus illustrated in Fig. 3 is conditioned to respond to the impulses of the code selecting digit dialed at the calling substation. During each impulse, the calling subscriber's loop circuit is opened for an interval, in the usual manner, and the line relay R325 follows the impulses by alternately restoring and operating. Each time R325 restores, the above-mentioned circuit is completed for energizing R335 in parallel with the magnet 379, this circuit extending from ground at RA326 and its associated upper contact to RA332 and its associated lower contact, where it divides, one branch extending by way of the winding of R335 to battery and the other branch extending by way of RA343 and the winding of the magnet 379 to battery. Each time the magnet 379 is energized, it attracts its operating armature, not shown, to condition the associated ratchet and pawl mechanism to step the wiper 382 one step and thereafter, when it is deenergized, the associated ratchet and pawl mechanism performs the stepping operation. When the wiper 382 takes its first step, the off-normal springs 380 are closed to prepare a circuit, traced hereinafter, for energizing R340. It will be understood that, at the end of the code selecting digit, the wiper 382 is left standing in engagement with the contact of the set 381 corresponding to the particular code identifying the called substation. For example, if the substation A' is being called and the code call designating this substation corresponds to the code of the ringing voltage applied to the third conductor terminating at the set 381, the code selecting digit will necessarily comprise three impulses so that, at the conclusion thereof, the wiper 382 will be left standing in engagement with its associated third contact.

Shortly following the conclusion of the code selecting digit and with R325 in its operated position, the relay R335 restores to complete the above-mentioned circuit for energizing R340, this circuit extending from ground at RA336 by way of RA342, the off-normal springs 380 and the winding of R340 to battery. Upon operating the relay R340 completes, at RA341, a holding circuit for itself, this circuit extending from ground at RA341 by way of RA342, the off-normal springs 380 and the winding of R340 to battery. At RA343, the relay R340 interrupts a point in the

above-traced impulsing circuit extending to the operating magnet 379 and, at RA344, the relay R340 further prepares the circuit, mentioned above, for energizing the release magnet 378.

The arrangement of the apparatus is such that 5 ringing current is projected over the line 486 during a ringing operation for a predetermined number of code cycles only, following which the ringing current path is interrupted. More particularly, a ground pulse is applied to the pick-up 10 lead C366' at the beginning of each code cycle by the interrupter 395, and when the first ground pulse is applied to C366' following the operation of R340, a circuit for energizing R365 is completed, this circuit extending by way of RA345, 15 RA367 and its associated upper contact, and the lower winding of R365 to battery. When its lower winding is energized over the circuit just traced, the relay R365, which is of the two-step type, only partially operates to complete, at 20 RA366, a path for short-circuiting its upper winding, this path extending from ground as applied to the pick-up conductor C366' by way of RA345, RA367 and its associated upper contact, the upper winding of R365, and RA366 to the grounded con- 25 trol conductor C482. At the end of the ground pulse applied to C366', the above-traced short-circuiting path is obviously interrupted, permitting the two windings of R365 to be energized in series. The relay R365 now completes its opera- 30 tion and, in so doing, interrupts, at RA367 and the associated upper contact, a point in the above-traced circuit for energizing its lower winding. At RA368 and its associated upper contact, the relay R365 completes a path for projecting coded 35 ringing current out over the called line 486. The path of this current extends from the ungrounded terminal of the ringing generator 390, by way of the ringing interrupter 395, the ringing current conductor terminating at the third contact of the 40 set 381, the wiper 382, RA376 and its associated upper contact, RA368 and its associated upper contact, the line conductor 486, the condenser 487 and the ringer, not shown, at the called substation A', to the grounded terminal of the ring- 45 ing current generator. Portions of the ringing current also flow through the ringing devices individually provided at the other substations associated with the line 486, but the coded nature of the ringing indicates to the respective parties 50 that only the substation A' is being called. It will be noted that a portion of the ringing current also flows through the drop provided at the operator's station in the manual office 480 to actuate this device. As is well known, this device operates in 55 the manner of a buzzer to inform the operator that her assistance is not needed in completing the desired connection.

At the end of the first ringing cycle, the ringing interrupter 395 applies a second ground pulse 60 to the pick-up conductor 366', thereby to complete a circuit for energizing the lower winding of R370, this circuit extending by way of RA345, RA367 and its associated lower contact, RA372 and its associated upper contact and the lower 65 winding of R370 to battery. The relay R370, like the relay R365, is of the two-step type and, hence, it only partially operates when its lower winding is energized. Upon partially operating, the relay R370 completes, at RA371, a path for short-cir- 70 cuiting its upper winding, which path is substantially identical to that, traced above, for the upper winding of R365. At the end of the ground pulse applied to the pick-up conductor, this short-cir- 75 cuiting path is interrupted, permitting the two

windings of R370 to be energized in series. The relay R370 now completes its operation to interrupt, at RA372 and its associated upper contact, the above-traced circuit for energizing its lower winding and to prepare, at RA372 and its associated lower contact, a circuit for energizing the winding of R375. During the interval between the end of the second code cycle and the beginning of the third code cycle, and when ground is again applied to the pick-up conductor C366', the above-mentioned circuit is completed for energizing the winding of R375, this circuit extending by way of RA345, RA367 and its associated lower contact, RA372 and its associated lower contact, RA378 and the winding of R375 to battery. When its winding is energized over the above-traced circuit, the relay R375 first closes the "X" contacts associated with RA377 to complete a holding circuit for itself, this circuit extending from the grounded control conductor C482 by way of RA377 and the winding of R375 to battery. Shortly after the completion of this holding circuit, the relay R375 interrupts, at RA378, its operating circuit as traced above and, at RA376 and its associated upper contact, interrupts a point in the above-traced path for projecting ringing current over the called line 486. At RA376 and its associated lower contact, the relay R375 extends the talking loop to the called substation A'. When the call is answered at the called substation, the desired conversational circuit is fully established. The portion of this circuit extending between the calling substation E and the repeater 315 will readily be apparent from an inspection of the drawings. The remaining portion of this circuit, namely, that extending from the repeater 315 to the called substation A', extends from ground at the upper terminal of the repeater winding 316, by way of this winding, the condenser 316', the repeater winding 317, RA323', RA376, RA368, the line conductor 486, the condenser 487 and the telephone substation equipment at the substation A', back to the ground return side of the line.

The release of the connection as established between the substations E and A', in the manner just described, is entirely under the control of the party at the calling substation E. More particularly, when the calling party hangs up, the three switches 310, 305 and 300 are released, in the order named and in the manner pointed out previously. When the call is cleared out at the calling substation, multiple ground is removed from the control conductor C482 in the connector switch 310 and the loop circuit over which the line relay R325 is being held energized is interrupted. When R325 restores, it interrupts, at RA326, the operating circuit for the hold relay R330, causing the last-mentioned relay to restore, after an interval, to remove ground from the control conductor C482 at its armature RA331. At RA332, the relay R330, upon restoring, completes the above-mentioned circuit for energizing the release magnet 378, this circuit extending from ground at RA326 by way of RA332 and its associated upper contact, RA344 and the winding of the magnet 378 to battery. When the magnet 378 is energized, the wiper 382 is returned to its home position in a well-known manner, at which time the off-normal springs 380 are opened to interrupt the holding circuit for R340. When R340 restores, it opens a further point in its holding circuit, prepares the circuit for energizing the operating magnet 379, and interrupts, at

RA344, the operating circuit for the release magnet 378.

When R330 restores to remove ground from the control conductor C482, battery potential is impressed on the control conductor to mark the line as idle. More specifically, the marking path extends from battery by way of the winding of R320, RC353, RA351, C483, RC432, and RA431 to the control conductor C482. The removal of ground from C482 results in the interruption of the common portion of the holding circuits for the three relays R365, R370 and R375, causing all of these relays to restore. Following the above-described sequence of operations, the connection is entirely released, the line 486 is marked as idle, and the apparatus is in readiness for further use.

Although, in the operation of the apparatus as just described, the ringing operation is automatically performed in response to the dialing of the proper code selecting digit at the calling substation, it will be understood that the operator in the manual office 480 may, if desired, be called upon to signal the desired called substation by ringing back over the called line. More particularly, the code of the ringing current applied to one of the ringing current conductors extending to the contacts of the contact set 381 may correspond to the coded ring identifying the operator's telephone station as the station being called. If, for example, the code of the ringing voltage applied to the first conductor terminating at the first contact of the set 381 is the code identifying the operator's telephone station, and the assistance of the operator in completing the call is desired, the calling party may, by dialing a code selecting digit consisting of one impulse, cause ringing current to be projected over the line of the proper code to indicate to the operator that her station is being called. It will be understood that the operation of the ringing apparatus to project ringing current of the selected code over the called line to the operator's station is in all respects identical with the operation of the apparatus as described above. Also, the manner in which the operator answers the call and operates her ringing key to project coded ringing current of the proper code back over the called line may be substantially similar to that described above with reference to the system illustrated in Figs. 1 and 2.

The manner in which a connection is completed between one of the rural substations associated with the line 486 and one of the automatic subscribers' substations on a call initiated at the rural substation depends upon the nature of the last-mentioned substation. More particularly, if the calling rural substation is of the fully automatic type and is equipped with an impulsing device, the calling party may cause the desired connection to be set up without any assistance on the part of the operator in the manual office 480. On the other hand, if the calling substation is of the magneto type and is not provided with impulsing means, the assistance of the operator in the manual office is necessary in securing the desired connection. For example, if a party at the substation A' desires a connection with one of the automatic subscribers' substations, as, for example, the substation E, the calling party may initiate the call by actuating the magneto generator provided at the substation A' in accordance with the code identifying the operator's telephone station in the manual office 480. The resulting operation of the signal device provided at the

operator's station indicates to the operator that a call awaits attention. A portion of the ringing current projected over the line 486 is conducted through the upper winding of R350, causing this relay to operate. When the call is answered, and as was explained above with reference to the apparatus illustrated in Fig. 2 of the drawings, a talking connection is established between the operator's telephone and the calling substation. 8

10 Also, ground is applied to the line conductor 486 to complete a circuit for energizing the relay R415, this circuit extending from ground on the conductor noted by way of RA368 and its associated lower contact, RA354, the repeater winding 15 317, RA323, C481 and the winding of R415 to battery. When its upper winding is energized by the ringing current projected over the line 486 the relay R350 first attracts its armature RA355 to complete, at the "X" contacts associated with 20 this armature, an obvious holding circuit for itself. Thereafter, the relay R350 completes, at RA354, an obvious path for short-circuiting its upper winding, thereby to exclude this winding from the talking and impulsing circuits. At 25 RA351 and RC352 the relay R350 completes a path for applying ground to the control conductor C482, which path extends from ground at RC352 by way of RA351, C483, RC432 and RA431 to the control conductor noted. When ground is 30 applied to this control conductor, the line 486 is marked as busy in the bank contacts of the numerical switches to which the trunk line 346 extends. At RA356, the relay R350 prepares a circuit, traced hereinafter, for energizing the upper winding of the release relay R360 and, at RA357, the relay R350 prepares a holding circuit for R360. 35

40 The relay R415 operates substantially simultaneously with the operation of R350 and, upon operating, completes, at RA419, a circuit for energizing R420, this circuit extending from ground at RA434 by way of RC435, RA419 and the winding of R420 to battery. At RA416 and RC417, the relay R415 opens a point in its priming circuit, and, at RA416 and RC418, it prepares a point in one of the holding circuits for R430. 45 When R420 operates, it completes, at RA424, a holding circuit for itself, this circuit extending from ground by way of the resistor 426, RA424, RA419 and the winding of R420 to battery. At RA425, the relay R420 opens a point in the circuit, traced hereinafter, for energizing the lower winding of R440 and, at RA421 and RC422, it completes an obvious circuit for energizing the 50 slow-to-release hold relay R430.

55 When R430 operates, it completes, at RA431 and RC433, an obvious alternative path for applying ground to the control conductor C482 and, at RA434 and RC435, it interrupts a point in the above-traced operating circuit for R420. At RA434 and RC436, the relay R430 completes the above-mentioned holding circuit for itself, this circuit extending by way of RA416, RC418 and the winding of R430 to battery. At RA431, the relay R430 prepares a circuit, traced hereinafter, for energizing the lower winding of R450. At 60 RA438 and RC439, the relay R430 opens a point in the circuit, traced hereinafter, for energizing the release magnet 472 and, at RA438 and RC438', it prepares a holding circuit, traced hereinafter, for the slow-to-operate relay R440. With the four relays R350, R415, R420 and R430 operated, the apparatus in the repeater terminating the 65 line 486 is conditioned to respond to the impulses 70

of the first or prefix digit dialed at the operator's telephone in the manual office 480.

75 The arrangement illustrated in Figs. 3 and 4 is similar to that illustrated in Figs. 1 and 2 in that the dialing of a prefix digit of ten impulses is a prerequisite to the extension of the connection to the non-numerical line switch 400. The purpose of providing this arrangement is the same as that stated previously in the description of the apparatus illustrated in Figs. 1 and 2, namely, to prevent any of the regular automatic switching equipment provided in the automatic exchange from being uselessly tied up when reverting calls are initiated on the line 486. During the dialing of the prefix digit, the four relays R415, R420, 10 R440 and R450 respond to the impulses thereof and function to repeat corrected impulses to the operating magnet 471 of the switch 470. More particularly, at the beginning of the first impulse of the prefix digit, and when the line circuit is 15 opened at the impulsive device provided at the operator's telephone station, the line relay R415 restores to interrupt, at RA419, the above-traced holding circuit for R420 and to complete, at RA416 and RC417, a priming circuit for itself. 20 The last-mentioned circuit extends from ground at RA434 by way of RA436, RA416, RC417, the resistor 417' and the winding of R415 to battery. It is pointed out that the resulting energization of R415 is insufficient to cause the operation of 25 this relay and that such energization is provided for the purpose of rendering this relay more sensitive in its operation when the line circuit is subsequently closed at the end of the open circuit pulse. When R415 restores, it not only completes 30 its priming circuit, in the manner pointed out above, but interrupts, at RA416 and RC418, the above-traced holding circuit for R430. Due to its slow-to-release characteristic, however, the last-mentioned relay remains operated during 35 40 impulsive. When the holding circuit for R420 is interrupted at RA419 upon the restoration of R415, the relay R420 restores to open, at RA421 and RC422, the operating circuit for R430 and to complete, at RA421 and RC423, the prepared circuit for energizing the lower winding of R450, 45 this latter circuit extending from ground at RA421 by way of RC423, RA437, RA441 and the lower winding of R450 to battery. Upon operating, the relay R450 completes, at RA453, a path for short-circuiting its upper winding, thereby to render 50 itself slow-to-release. At RA452, the relay R450 completes an alternative and obvious holding circuit for the hold relay R430. At RA455, the relay R450 completes a circuit for energizing R440, 55 this circuit extending by way of the resistor 427, the restored armature RA425 and the lower winding of R440 to battery. Since the upper winding of R440 is normally short-circuited at RA443, this relay is slow to operate. After an interval, however, R440 operates to complete, at RA444, 60 the above-mentioned holding circuit for itself, this circuit extending from ground at RA438 by way of RC438', RA444, the resistor 427, RA425 and the lower winding of R440 to battery. At RA441, the relay R440 interrupts the above-traced circuit for energizing the lower winding of R450 and, at RA442, it prepares an alternative operating circuit for R420. At the end of 65 the first open circuit pulse, and when the impulsive springs of the impulsive device located at the operator's station in the exchange 480 are again closed, the relay R415 reoperates to interrupt, at RA416 and RC417, its priming circuit and to recomplete, at RA416 and RC418, the holding circuit for R430. At RA419, the relay R415 70 75

completes the above-mentioned alternative operating circuit for R420, this circuit extending from ground at RA442 by way of RA419 and the winding of R420 to battery. The relay R420, upon 5 reoperating, completes, at RA424, its holding circuit as traced above and opens, at RA425, the holding circuit for R440, causing the last-mentioned relay to restore. At RA421 and RC422, the relay R420 recompletes the operating circuit 10 for R430 and, at RA421 and RC423, it interrupts a further point in the above-traced circuit for energizing the lower winding of R450. After an interval following the deenergization of its lower winding, the relay R450 restores to open, at 15 RA455, the above-traced operating circuit for R440 and to interrupt, at RA452, a point in the above-mentioned alternative holding circuit for R430. During each succeeding impulse following the first, the four relays R415, R420, R440, and 20 R450 operate in the sequence just described. Since in the present assumed case the preliminary digit dialed at the operator's station comprises ten impulses, it will be understood that, during this digit, the cycle of operation of the relays 25 noted is repeated ten times. The relay R450 is the pulsing relay and it will be apparent from the foregoing description that the relation between the period of deenergization and the period of energization of this relay during each impulse 30 is, within limits, independent of the relation of the corresponding periods for the line relay R415. More particularly, the operation of R415 at the beginning of each impulse cycle initiates the operation of the three relays R420, R440 and R450 35 to repeat the impulse, and the extent of the period during which R450 is energized depends primarily upon the slow-to-release characteristic of this relay and the slow-to-operate characteristic of R440.

40 During the period of each impulse when the pulsing relay R450 is operated, a circuit is completed for energizing the operating magnet 471 of the switch 470, this circuit extending from ground at RA454 by way of RA463 and the winding of the magnet 471 to battery. Obviously, at 45 the end of the first and each succeeding impulse, the above-traced circuit for energizing the magnet 471 is opened. Each time this magnet is de-energized following its energization, it steps the wiper 475 one step so that, at the end of the pre- 50 liminary digit, the wiper noted will be left standing in engagement with the tenth contact of the set 474, assuming that the line relay R415 is faithfully responsive to the impulses dialed at the operator's station in the distant office 480. When 55 the first step is taken by the wiper 475, the off-normal springs 473 are closed to prepare a circuit, traced hereinafter, for energizing the release magnet 472. This circuit is held interrupted at the operated armature RA438 of the hold relay R430 for the duration of the call.

If the wiper of the switch 470 is successfully operated into engagement with its associated tenth contact in response to the dialing of the preliminary or prefix digit at the operator's station, an obvious circuit is completed for energizing R460 immediately the wiper 475 is moved into engagement with the tenth contact of the set 474. Upon operating, the relay R460 interrupts, at RA463, a point in the above-traced circuit for energizing the operating magnet 471, thereby to prevent further actuation of the impulsing device at the operator's station from causing further operation of the switch 470. At RA463', the relay R460 completes a multiple path including the two

conductors C488 and C489 for short-circuiting the upper winding of R350. At its armatures RA461 and RA462, the relay R460 completes a loop circuit to the non-numerical line switch 400 and including the trunk line 346. More particularly, this loop circuit extends from one terminal of the line relay conventionally provided in the switch 400 by way of RA462, C485, the repeater winding 318, RA321 and its associated upper contact, the resistor 312, the repeater winding 319, C484, RA451 and RA461 to the opposite terminal of the line relay embodied in the line switch 400. In response to the completion of this loop circuit, the line switch 400 operates to select a trunk leading to an idle selector switch. If it be assumed, for example, that the switch 405 is the first available idle selector switch, the line switch 400, upon seizing the trunk extending to this selector switch, operates to extend the loop circuit thereto, whereupon this selector switch is conditioned to respond to the impulses of the second digit dialed at the operator's station.

During the impulses of this second digit, the four relays R415, R420, R440 and R450 respond, in the exact manner pointed out above. Each time the relay R450 operates, it interrupts, at RA451, the above-traced loop circuit which is now extended to the selector switch 405. Thus, the impulses dialed at the operator's station are repeated to the selector switch noted and this selector switch responds thereto by selecting the group of connector switches having access to the called line 301 and including the switch 410. Shortly following the conclusion of the second digit, the selector switch 405 automatically operates to select a trunk leading to an idle connector switch in the selected group. If it be assumed, for example, that the switch 410 is the first available idle switch of the selected group, when the trunk leading to this connector switch is seized, the loop circuit is extended thereto and the switch is conditioned to respond to the impulses of the third and fourth digits dialed at the operator's station. The connector switch 410 operates in a conventional manner to select the called line 301 in response to the final two digits, to test the condition of the line, to return busy tone over the established loop to the operator in the distant manual office in the event the line is found busy, and to project ringing current over the called line 301 in the event the line is idle. The desired talking connection is completed between the calling and called substations when the call is answered at the substation E. The operator at the office 480 retains her answer plug in the jack terminating the line 486 during the interval when the line is occupied with the call.

In the illustrated arrangement, no provision is made for giving the manual office operator a disconnect signal. It will be understood, however, that a relay, corresponding to R160 illustrated in Fig. 1 of the drawings, may be included in the repeater for performing this function. In such case, the winding of the relay corresponding to R160 would be substituted for the resistor 312 and this relay would be provided with an armature for short-circuiting a resistance element provided in the series circuit over which R415 and the upper winding of R450 are energized. In any case, the release of the connection as established in the manner just described is entirely under the control of the operator in the manual office 480 who, upon ascertaining that the conversation is completed, may initiate the release of the operated apparatus by withdrawing the answer plug from

the jack terminating the line 486. When this is done, ground is removed from the line conductor 486 to interrupt the circuit over which R415 is being held energized. Upon restoring, the relay 5 R415 interrupts, at RA419, the holding circuit for R420, causing the last-mentioned relay to restore to interrupt, at RA421 and RC422, the operating circuit for R430 and to complete, at RA421 and RC423, the operating circuit for R450. When 10 R450 operates, it completes, at RA455, the circuit for energizing the lower winding of R440 and, at RA452, the above-traced holding circuit for R430. When R440 operates, it interrupts, at RA441, the operating circuit for R450, causing the last-mentioned relay to restore after an interval to open, at RA452, the remaining holding circuit for R430 and, at RA455, the operating circuit for R440. When, shortly thereafter, R430 restores, it interrupts, at RA438 and RC438', the completed holding 15 circuit for R440, causing the last-named relay to restore. At RA437, the relay R430 interrupts a further point in the operating circuit for R450. At RA431 and RC433, the relay R433 momentarily removes ground from the control conductor C482, 20 but ground is restored to this conductor upon the complete restoration of RA431, this second ground extending from RC352 to C482 over a path traced previously. At RA438 and RC439, the hold relay R430, upon restoring, completes a circuit extending 25 by way of the off-normal springs 473 for energizing the release magnet 472. When the release magnet 472 is energized, it causes the wiper 475 to be restored to its home position, at which time the off-normal springs 473 are opened to 30 interrupt the circuit for energizing the release magnet 472. The wiper 475, upon leaving its associated tenth contact, opens the operating circuit for R460, causing this relay to restore to interrupt the loop circuit extending to the operated 35 switch train comprising the switches 400, 405 and 410. Thus, the automatic switches are caused to restore in a manner which will be apparent from the preceding description.

The arrangement of the apparatus is such that 45 the line busying ground may not be removed from the control conductor C482 immediately an established connection is cleared out. Thus, it is pointed out above that the relay R350 functions to hold ground on C482 so long as it remains 50 operated. Following its operation, this relay is entirely under the control of R360 which latter relay is, in turn, arranged to be controlled by the pulse generator 385. More particularly, when the first ground pulse is applied to C303 55 by the pulse generator 385, following the operation of R350, the upper winding of R360 is energized over a circuit extending by way of RA356. Upon operating, the relay R360 completes a holding circuit for itself, this circuit extending from 60 ground at RA357 by way of RA361 and the lower winding of R360 to battery. At RA362, the relay R360 prepares a path for short-circuiting the lower winding of R350 when a ground pulse is subsequently impressed on the second pulse lead 65 C304. If the established connection is released in the manner described above before this last-mentioned ground pulse is applied to C304 the relay R350 remains energized by way of its holding circuit to retain busying ground potential 70 on the control conductor C482. On the other hand, if the duration of the call is such that a ground pulse is applied to C304 before the connection is cleared out the relay R350 is caused to restore and busying ground potential is removed 75 from the control conductor C482 immediately the

connection is cleared out. In either case when the second ground pulse is applied to C304, the lower winding of R350 is short-circuited over a path extending by way of C384, RA362 and the lower winding noted to ground at RA355. When 5 this occurs, the relay R350 restores. If, at the time R350 restores, conversation is still being held over the established connection, the upper winding of R350 is short-circuited at the operated armature RA463' of the relay R460. Hence, 10 R350 cannot reoperate since the first operation in the release of the connection is the interruption of the circuit for energizing the upper or operating winding of this relay. Similarly, if the lower winding of R350 is short-circuited after 15 the connection is cleared out, this relay cannot reoperate since its operating circuit is open under these circumstances. When R350 restores after the connection is cleared out, it removes, at RA351 and RC352, ground potential from C482. 20 At RA351 and RC352, the relay R380 applies battery potential to this conductor over the path traced above, thus marking the line 486 as idle. At RA355, the relay R350 opens a point in its holding circuit and, at RA351, it interrupts the 25 holding circuit for R360 causing the last-mentioned relay to restore. Thus, the apparatus is entirely released and the line 486 is marked as idle in the bank contacts of the connector switches to which the trunk line 486 extends. 30

The manner in which the apparatus illustrated in Figs. 3 and 4 operates when a call intended for one of the automatic subscribers' substations, such, for example, as the substation E, is initiated at one of the substations associated with 35 the line 486 and equipped for automatic service, is identical with that just described. In this case, however, and as was pointed out above, the intervention of the operator in the manual office 480 is not required since the necessary impulses 40 may be performed at the calling substation by the calling party.

With the arrangement illustrated in Figs. 3 and 4, it is contemplated that all reverting calls initiated at the substations associated with the 45 line 486 will be completed directly, or without the assistance of the operator in the manual office 480, means including the relays R350 and R360 and the pulse generator 385 being provided for marking the line as busy in the numerical 50 switches having access thereto during the periods when this line is occupied with calls of a reverting nature. Such calls may, of course, be forwarded to the desired substations through the intervention of the operator in the office 480 in 55 a manner substantially similar to that described previously with reference to the arrangement illustrated in Figs. 1 and 2. In either case, when the calling party actuates the magneto generator at the calling substation to project ringing current over the line 486, the upper winding of R350 is energized in the manner described above. Upon operating, the relay R350 performs the functions enumerated previously; that is, it short-circuits its upper winding, completes its holding circuit, and, at RA351 and RC352, applies ground to the control conductor C482. The relay R415 may or may not be caused to operate, depending upon the character of the substations to be used in the reverting call connection. If 70 one of these substations is equipped for full automatic service, or if the operator in the manual office is called upon to assist in completing the connection, a direct current circuit similar to that traced above will be completed for energ- 75

gizing R415. If R415 is caused to operate, it initiates the sequential operation of R420 and R430 in the manner pointed out previously. When R430 operates, it completes, at RA431, the above-noted alternative circuit for applying ground to C482 and prepares, at RA437, the operating circuit for R450. Since, in this case, no dialing is required in completing the reverting call connection, no further operations occur in the apparatus illustrated until the connection is released. During the interval when the line 486 is occupied with the call, however, and if the mode of completing the connection results in the energization of the three relays R415, R420 and R430, the line is guarded against seizure by any one of the numerical switches having access thereto through the application to ground to C482 occasioned by the continued energization of the hold relay R430.

If, on the other hand, the connection is established between two substations equipped for manual service only and without the assistance of the operator in the manual office, such that the relay R350 is alone energized, this relay functions to maintain busying ground on the control conductor C482. In this case busying ground is maintained on C482 for a predetermined time interval which is independent of the actual idle or busy condition of the line. More particularly, if the reverting call connection is cleared out before the pulse generator 385 and the relay R360 operate to cause the restoration of R350 in the manner set forth above, the last-mentioned relay is held energized over its holding circuit to maintain the line 486 marked as busy even though the line is actually idle. Conversely, if the connection is not cleared out at the calling and called substations until after the second ground pulse is applied to C304, following the operation of R350, this relay restores to remove, at RA351 and RC352, busying ground potential from C482 even though the line is still busy. Moreover, no circuit is available for causing the reoperation of R350, since in this case, no direct current circuit is established by way of the line 486 for energizing the relay R415.

In the case where one of the substations involved in the reverting call connection is equipped for automatic service or where the operator in the manual office intervenes in setting up the connection and remains plugged in on the connection until the conversation is terminated, the relay R350, in cooperation with the pulse generator 385 and the relay R360, functions to test the condition of the line at spaced intervals and to remove the busy marking when a test indicates that the line is idle. In this case the three relays R415, R420 and R430 are held energized for the duration of the call and the last-mentioned relay maintains busying ground on the control conductor C482. Assuming the connection is maintained for a considerable time interval, the pulse generator 385, in combination with R360, operates to cause the partial restoration of R350, in the manner described previously, after a given time interval. Upon partially restoring, R350 interrupts, at RA354, the path short-circuiting its upper winding, causing the winding to be energized in series with the winding of R415. Thus, R315 reoperates to recomplete its holding circuit and to reprepare, at RA356, the circuit for energizing the upper winding of R360 when a succeeding ground pulse is applied to C303. It will be apparent that so long as the connection is maintained the cycle of operations just described is repeated at spaced intervals. When the connection is ultimately cleared out ground is removed from the line conductor 486 and the relay R415 is caused to restore in the manner pointed out above. The restoration of R415 is followed by the restoration of R420, which latter relay, upon restoring, completes, at RA421 and RC423, the above-traced operating circuit for R450. The relay R450, upon operating, completes, at RA454, the above-traced circuit for energizing the magnet 471 and, at RA455, the previously traced operating circuit for R440. Thereafter and when R450 restores following the operation of R440, the wiper 475 of the switch 470 is operated one step off normal to close the off-normal springs 473. When R450 restores, it also opens the only remaining holding circuit for R430, causing the last-mentioned relay to restore, after an interval, to complete, at RA438 and RC439, the above-traced circuit for energizing the release magnet 472. When the release magnet is energized the switch 470 is restored to normal and the off-normal springs 473 are opened to interrupt the circuit for energizing the release magnet. When R430 restores, it interrupts, at RA438 and RC438, the holding circuit for R440, causing the last-mentioned relay to restore. At RA431, the relay R430 disconnects the control conductor C482 from ground at RC433 and connects it to ground at RC352. When thereafter the relay R350 is caused to restore in the manner described above, no circuit is available for energizing the upper winding thereof and hence this relay remains in its restored position. Upon restoring, following the restoration of R430, the relay R350 disconnects the control conductor C482 from ground at RA351 and RC352 and completes the above-traced path for applying battery potential thereto. Thus, the line is marked as idle and the apparatus embodied in the repeater terminating the line is restored to normal.

While there have been described what are at present considered to be the preferred embodiments of the invention, it will be understood that various modifications may be made therein, and it is intended in the appended claims to cover all such modifications as fall within the true spirit and scope of the invention.

We claim:

1. In a telephone system, a telephone station, a ringing current generator at said station, an automatic exchange, a line extending between said station and said exchange, a plurality of substations associated with said line, a plurality of additional lines extending to said exchange, automatic switching equipment in said exchange for setting up connections between said additional lines and between said first-named line and said additional lines, and control apparatus associated with said first-named line; said apparatus being so connected and arranged that a call to one of said substations initiated on one of said additional lines and extended through a portion of said automatic switching equipment is routed over said first-named line to said station and said one station is thereafter signaled by projecting ringing current from said generator back over said first-named line to said one substation, a call to one of said substations initiated at another of said substations is routed over said first-named line to said station and said one substation is signaled by projecting ringing current from said generator back over said first-named line to said one substation, and a call to one of said additional lines initiated at one of said substations is routed over said first-named line to said station and is then routed from said station to said exchange.

tion back over said first-named line and through a portion of said automatic switching equipment to said one additional line.

2. In a telephone system, a telephone station, 5 a ringing current generator at said station, an automatic exchange, a line extending between said station and said exchange, a substation associated with said line, a plurality of additional lines extending to said exchange, automatic 10 switching equipment in said exchange for setting up connections between said additional lines and between said first-named line and said additional lines, and control apparatus associated with said first-named line, said apparatus being so 15 connected and arranged that a call to said substation initiated on one of said additional lines and extended through a portion of said automatic switching equipment is routed over said first-named line to said station and said substa- 20 tion is thereafter signaled by projecting ringing current from said generator back over said first-named line to said substation, and a call to one of said additional lines initiated at said substa- 25 tion is routed over said first-named line to said station and is then routed from said station back over said first-named line and through a portion of said automatic switching equipment to said one additional line.

3. In a telephone system, a telephone station, 30 a ringing current generator at said station, an automatic exchange, a line extending between said station and said exchange, a plurality of substations associated with said line, a plurality of additional lines extending to said exchange, 35 automatic switching equipment in said exchange for setting up connections between said additional lines and between said first-named line and said additional lines, and control apparatus associated with said first-named line; said ap- 40 paratus being so connected and arranged that a call to one of said substations initiated at another of said substations is routed over said first-named line to said station and said one substa- 45 tion is signaled by projecting ringing current from said generator back over said first-named line to said one substation, and a call to one of said additional lines initiated at one of said substations is routed over said first-named line to said station and is then routed from said station 50 back over said first-named line and through a portion of said automatic switching equipment to said one additional line.

4. In a telephone system, a telephone station, 55 a ringing current generator at said station, an automatic exchange, a line extending between said exchange and said station, a plurality of substations associated with said line, a plurality of additional lines extending to said exchange, automatic switching equipment in said exchange 60 for setting up connections between said additional lines and between said first-named line and said additional lines, and control apparatus associated with said first-named line; said apparatus being so connected and arranged that a 65 call to one of said substations initiated on one of said additional lines and extended through a portion of said automatic switching equipment is routed over said first-named line to said station and said one substation is thereafter signaled by 70 projecting ringing current from said generator back over said first-named line to said one substation, and a call to one of said substations initiated at another of said substations is routed over said first-named line to said station and said one substation is then signaled by projecting 75

ringing current from said generator back over said first-named line to said one substation.

5. In a telephone system, a telephone station, 5 a ringing current generator at said station, an automatic exchange, a line extending between said station and said exchange, a substation associated with said line, a plurality of additional lines extending to said exchange, automatic switching equipment in said exchange for setting up connections between said additional lines and between said first-named line and said additional lines, and control apparatus associated with said first-named line; said apparatus being so connected and arranged that a call to said substation initiated on one of said additional lines 10 and extended through a portion of said automatic switching equipment is routed over said first-named line to said station and said substation is thereafter signaled by projecting ringing current from said generator back over said first-named line to said substation. 20

6. In a telephone system, a telephone station, 25 a ringing current generator at said station, an automatic exchange, a line extending between said station and said exchange, a plurality of substations associated with said line, a plurality of additional lines extending to said exchange, automatic switching equipment in said exchange for setting up connections between said additional lines and between said first-named line and said additional lines, and control apparatus associated with said first-named line; said apparatus being so connected and arranged that a call to one of said additional lines initiated at one of said substations is routed over said first-named line to said station and is then routed from said station back over said first-named line and through a portion of said automatic switching equipment to said one additional line. 35

7. In a telephone system, a manual office, an 40 operator's telephone station in said office, a ringing current generator at said station, an automatic exchange, a trunk line of the ground return type extending between said automatic exchange and said station, a plurality of substations associated with said line and each including telephone substation equipment connected between ground and the ungrounded side of said line, a plurality of additional lines extending to said automatic exchange, automatic switching equipment in said automatic exchange for setting up connections between said additional lines and between said first-named line and said additional lines, and control apparatus associated with said first-named line; said apparatus being so 45 connected and arranged that a call to one of said substations initiated on one of said additional lines and extended through a portion of said automatic switching equipment is routed over said first-named line to said station and said one substation is thereafter signaled by projecting ringing current from said generator back over said first-named line to said one substation, a call to one of said substations initiated at another of said substations is routed over said first-named line to said station and said one substation is signaled by projecting ringing current from said generator back over said first-named line to said one substation, and a call to one of said additional lines initiated at one of said substations is 50 routed over said first-named line to said station and is then routed from said station back over said first-named line and through a portion of said automatic switching equipment to said one additional line. 55

8. In a telephone system, a manual office, an operator's telephone station in said office, a ringing current generator at said station, an automatic exchange, a trunk line of the ground return type extending between said automatic exchange and said station, a plurality of substations associated with said line and each including telephone substation equipment connected between ground and the ungrounded side of said line, a plurality of additional lines extending to said automatic exchange, automatic switching equipment in said automatic exchange for setting up connections between said additional lines and between said first-named line and said additional lines, and control apparatus associated with said first-named line; said apparatus being so connected and arranged that a call to one of said substations initiated on one of said additional lines and extended through a portion of said automatic switching equipment is routed over said first-named line to said station and said one substation is thereafter signaled by projecting ringing current from said generator back over said first-named line to said one substation, a call to one of said substations initiated at another of said substations is routed over said first-named line to said station and said one substation is signaled by projecting ringing current from said generator back over said first-named line to said one substation, and a call to one of said additional lines initiated at one of said substations is routed over said first-named line to said station and is then routed from said station back over said first-named line and through a portion of said automatic switching equipment to said one additional line; and means in said automatic exchange and controllable from said station for marking said first-mentioned line as busy, thereby to prevent its seizure by said automatic switching equipment.
9. In a telephone system, a telephone station, a signal device at said station, a control relay operative to cause the operation of said signal device, an automatic exchange, a line including at least one conductor extending between said exchange and said station, an additional line extending to said exchange, automatic switching equipment in said exchange and operative to set up a connection between said additional line and said first-named line, a substation adapted to be connected to said additional line, a line relay in said exchange and associated with said first-named line, a circuit for energizing said control relay and said line relay in series, said circuit including one conductor of said first-named line, and means controllable from said substation over said additional line for controlling said control relay without interfering with the operation of said line relay.
10. In a telephone system, a telephone station, a signal device at said station, a control relay operative to cause the operation of said signal device, an automatic exchange, a line including at least one conductor extending between said exchange and said station, an additional line extending to said exchange, automatic switching equipment in said exchange and operative to set up a connection between said additional line and said first-named line, a substation adapted to be connected to said additional line, a line relay in said exchange and associated with said first-named line, a circuit for energizing said control relay and said line relay in series, said circuit including one conductor of said first-named line, a resistor arranged to be included in said circuit, a third relay including contacts for including said resistor in said circuit, said control relay being so constructed and arranged that it is operated when said resistor is not included in said circuit and is restored when said resistor is included in said circuit.
11. In a telephone system, a telephone station, a signal device at said station, a control relay operative to cause the operation of said signal device, an automatic exchange, a repeater in said exchange, a line extending between said repeater and said station, automatic switching equipment in said exchange, a trunk line extending to said repeater and terminating in said automatic switching equipment, said trunk line including a pair of conductors, means included in said automatic switching equipment for applying direct voltage of one polarity between the conductors of said trunk line, means included in said automatic switching equipment for reversing the polarity of the voltage applied between the conductors of said trunk line, a line relay in said exchange and associated with said first-named line, a circuit for energizing said control relay and said line relay in series, said circuit including one conductor of said first-named line, and means comprising a polarized relay having a winding connected across the conductors of said trunk line for controlling said control relay without interfering with the operation of said line relay.
12. In a telephone system, a telephone station, a signal device at said station, a control relay operative to cause the operation of said signal device, an automatic exchange, a repeater in said exchange, a line extending between said repeater and said station, automatic switching equipment in said exchange, a trunk line extending to said repeater and terminating in said automatic switching equipment, said trunk line including a pair of conductors, means included in said automatic switching equipment for applying direct voltage of one polarity between the conductors of said trunk line, means included in said automatic switching equipment for reversing the polarity of the voltage applied between the conductors of said trunk line, a line relay in said exchange and associated with said first-named line, a circuit for energizing said control relay and said line relay in series, said circuit including one conductor of said first-named line, a resistor arranged to be included in said circuit, a polarized relay having a winding connected across the conductors of said trunk line whereby said polarized relay responds to reversals of the polarity of the voltage applied between said trunk line conductors, and contacts controlled by said polarized relay for including said resistor in said circuit, said control relay being so constructed and arranged that it is operated when said resistor is not included in said circuit and is restored when said resistor is included in said circuit.
13. In a telephone system, an exchange, a plurality of lines extending to said exchange, a plurality of non-numerical switches and a plurality of impulse responsive numerical switches in said exchange, means including said switches for setting up connections between said lines, a repeater in said exchange, an additional line extending to said exchange and terminating at said repeater, a telephone station to which said

- additional line extends, a signal device at said station, a trunk line terminating in certain of said numerical and non-numerical switches and extending to said repeater, means included in 5 said repeater for connecting said additional line by way of said trunk line through to one of said non-numerical switches on a call initiated on said additional line, a pair of relays included in said repeater, one of said relays being operative 10 to cause ringing current to be projected over said additional line on a call initiated on one of said plurality of lines and routed by way of certain of said switches, the other of said relays only being operative an interval following the 15 operation of said one relay, and means responsive to the operation of said other relay for discontinuing the projection of ringing current over said additional line.
14. In a telephone system, an exchange, a plurality of lines extending to said exchange, a plurality of non-numerical switches and a plurality of impulse responsive numerical switches in said exchange, means including said switches for setting up connections between said lines, a repeater in said exchange, an additional line extending to said exchange and terminating at 20 said repeater, a telephone station to which said additional line extends, a signal device at said station, a trunk line terminating in certain of said numerical and non-numerical switches and extending to said repeater, said trunk line including at least one conductor, means included in those of said numerical switches having access to said trunk line for applying a predetermined 25 potential to said one conductor following the selection of said trunk line, means included in said repeater for connecting said additional line by way of said trunk line through to one of said non-numerical switches on a call initiated on 30 said additional line, a ringing current generator associated with said repeater, a pair of relays included in said repeater, one of said relays being operative in response to the application of said predetermined potential to said one conductor of said trunk line, means responsive to the 35 operation of said one relay for connecting said ringing current generator to project ringing current over said additional line thereby to actuate said signal device, the other of said relays being operative an interval following the operation of 40 said one relay, and means responsive to the operation of said other relay for disconnecting said ringing current generator from said additional line.
15. In a telephone system, an exchange, a plurality of lines extending to said exchange, a plurality of non-numerical switches and a plurality of impulse responsive numerical switches in said exchange, means including said switches for setting up connections between said lines, an impulse responsive test link in said exchange, an additional line extending to said exchange and terminating at said test link, a telephone station to which said additional line extends, a signal device at said station, an impulsive device at 45 said station, a trunk line terminating in certain of said numerical and non-numerical switches and extending to said test link, means included in said test link and responsive to a predetermined series of impulses transmitted thereto from said impulsive device and over said additional line for connecting said additional line by way of said trunk line through to one of said non-numerical switches, and means included in said link and responsive to the seizure 50 of said trunk line by one of said numerical switches for projecting ringing current over said additional line thereby to actuate said signal device.
16. In a telephone system, an exchange, a plurality of lines extending to said exchange, a plurality of non-numerical switches and a plurality of impulse responsive numerical switches in said exchange, means including said switches for setting up connections between said lines, an impulse responsive test link in said exchange, an additional line extending to said exchange and terminating at said test link, a telephone station to which said additional line extends, a signal device at said station, an impulsive device at 55 said station, a trunk line terminating in certain of said numerical and non-numerical switches and extending to said test link, means included in said test link and responsive to a predetermined series of impulses transmitted thereto from said impulsive device and over said additional line for connecting said additional line by way of said trunk line through to one of said non-numerical switches, a ringing current generator associated with said link, and means included in said link and responsive to the seizure 60 of said trunk line by one of said numerical switches for connecting said generator to project ringing current over said additional line, thereby to actuate said signal device.
17. In a telephone system, an exchange, a plurality of lines extending to said exchange, a plurality of non-numerical switches and a plurality of impulse responsive numerical switches in said exchange, means including said switches for setting up connections between said lines, an impulse responsive test link in said exchange, an additional line extending to said exchange and terminating at said test link, a telephone station to which said additional line extends, a signal device at said station, an impulsive device at 65 said station, a trunk line terminating in certain of said numerical and non-numerical switches and extending to said test link, means included in said test link and responsive to a predetermined operation of said impulsive device for connecting said additional line by way of said trunk line through to one of said non-numerical switches on a call initiated on said additional line, and means included in said test link for projecting ringing current over said additional line to actuate said signal device on a call initiated on one of said plurality of lines and routed by way of certain of said switches.
18. In a telephone system, an exchange, a plurality of lines extending to said exchange, a plurality of non-numerical switches and a plurality of impulse responsive numerical switches in said exchange, means including said switches for setting up connections between said lines, an impulse responsive test link in said exchange, an additional line extending to said exchange and terminating in said test link, a telephone station to which said additional line extends, a signal device at said station, an impulsive device at 70 said station, a trunk line terminating in certain of said numerical and non-numerical switches and extending to said test link, said trunk line including a control conductor adapted to have a predetermined potential applied thereto when said trunk line is seized by one of said numerical switches, means included in said link and responsive to a predetermined operation of said impulsive device for connecting said additional line by way of said trunk line through to 75

- one of said non-numerical switches, and means included in said link and responsive to the application of said predetermined potential to said control conductor during the seizure of said 5 trunk line by one of said numerical switches for projecting ringing current over said additional line thereby to actuate said signal device.
19. In a telephone system, an exchange, a plurality of lines extending to said exchange, a plurality of non-numerical switches and a plurality of impulse responsive numerical switches in said exchange, means including said switches for setting up connections between said lines, an impulse responsive test link in said exchange, an 10 additional line extending to said exchange and terminating at said test link, a telephone station to which said additional line extends, a signal device at said station, an impulsive device at said station, a plurality of substations associated with said additional line, a trunk line terminating in certain of said numerical and non-numerical switches and extending to said test link, means included in said test link and responsive to a predetermined operation of said impulsive device for connecting said additional line by way of said trunk line through to one of said non-numerical switches on a call initiated on said additional line, a source of ringing current, a plurality 15 of ringing current conductors arranged individually to be connected to said additional line to project ringing current thereover, a ringing interrupter for applying the voltage of said source to said ringing current conductors for coded intervals which are different for each of said conductors, whereby said substations may be selectively signaled by selectively connecting said conductors to said additional line, and means comprising a switch included in said test link and operative in response to impulses transmitted thereto over one of said plurality of lines on a call routed by way of said one of said plurality of lines for selecting the one of said ringing 20 current conductors to be connected to said additional line.
20. In a telephone system, a line, a relay having a winding normally included in said line, said winding being energized to cause the operation of said relay when a call is routed by way of said line, a normally open holding circuit for said relay, said relay comprising a second winding included in said holding circuit, means responsive to the operation of said relay for completing said 25 holding circuit, and means responsive to the operation of said relay for short-circuiting said first-named winding, thereby to exclude said first-named winding from a talking connection including said line.
21. In a telephone system, a line, a relay having a winding normally included in said line, said winding being energized to cause the operation of said relay when a call is routed by way of said line, a normally open holding circuit for said relay, said relay comprising a second winding included in said holding circuit, means responsive to the operation of said relay for completing said holding circuit, means responsive to operation of said relay for short-circuiting said first-named winding, thereby to exclude said first-named winding from a talking connection including said line, and means independent of said last-named means for short-circuiting said first-named winding even though said relay is deenergized.
22. In a telephone system, a line, an automatic switch having access to said line, a relay having a winding normally included in said line, said winding being energized to cause the operation of said relay when a call is initiated on said line, a normally open holding circuit for said relay, said relay comprising a second winding included in said holding circuit, means responsive to the operation of said relay for completing said holding circuit, means responsive to the operation of said relay for short-circuiting said first-named winding, thereby to exclude said first-named winding from a talking connection including said line, and means responsive to the seizure of said line by said switch for short-circuiting said first- 25

- named winding even though said relay is de-energized.
25. In a telephone system, an exchange, a plurality of lines extending to said exchange, a plurality of non-numerical switches and a plurality of impulse responsive numerical switches in said exchange, means including said switches for setting up connections between said lines, an additional line extending to said exchange, a telephone station associated with said additional line, an impulsive device at said station, a test link at which said additional line terminates, a trunk line terminating at certain of said non-numerical switches and certain of said numerical switches and extending to said test link, a relay having a winding included in said additional line, said winding being energized to cause the operation of said relay when a call is initiated at said station, a normally open holding circuit for said relay, said relay comprising a second winding included in said holding circuit, means responsive to the operation of said relay for completing said holding circuit, means responsive to the operation of said relay for short-circuiting said first-named winding, thereby to exclude said first-named winding from a talking connection including said line, means responsive to a predetermined operation of said impulsive device for connecting said additional line by way of said trunk line through to one of said non-numerical switches, and means including a portion of said last-named means for short-circuiting said first-named winding independently of said first-mentioned short-circuiting means.
35. 26. In a telephone system, an exchange, a plurality of lines extending to said exchange, a plurality of non-numerical switches and a plurality of impulse responsive numerical switches in said exchange, means including said switches for setting up connections between said lines, an additional line extending to said exchange, a telephone station associated with said additional line, an impulsive device at said station, a test link at which said additional line terminates, a trunk line terminating at certain of said non-numerical switches and certain of said numerical switches and extending to said test link, a relay having a winding included in said additional line, said winding being energized to cause the operation of said relay in response to the initiation of a call at said station, a normally open holding circuit for said relay, said relay comprising a second winding included in said holding circuit, means responsive to the operation of said relay for completing said holding circuit, means responsive to the operation of said relay for short-circuiting said first-named winding, thereby to exclude said first-named winding from a talking connection including said line, means responsive to a predetermined operation of said impulsive device for connecting said additional line through to one of said non-numerical switches, means including a portion of said last-named means for short-circuiting said first-named winding independently of said first-mentioned short-circuiting means, and means responsive to the seizure of said trunk
- line by one of said numerical switches for short-circuiting said first-named winding even though said relay is deenergized.
27. In a telephone system, a line, an automatic switch having access to said line, means operative when a call is routed by way of said line for marking said line as busy, thereby to prevent the seizure of said line by said switch, means for testing said line at spaced intervals to determine its idle or busy condition, and means for causing said first-named means to remove said busy marking when a test indicates said line is idle.
28. In a telephone system, a line, an automatic switch having access to said line, a relay operative when a call is routed by way of said line for marking said line as busy, thereby to prevent the seizure of said line by said switch, means including said relay for testing said line at spaced intervals to determine its idle or busy condition, and means for causing said relay to remove said busy marking when a test indicates said line is idle.
29. In a telephone system, a line, an automatic switch having access to said line, a relay operative when a call is routed by way of said line, means responsive to the operation of said relay for marking said line as busy thereby to prevent the seizure of said line by said automatic switch, a holding circuit for said relay, means responsive to the operation of said relay for completing said holding circuit and for maintaining said holding circuit completed independently of the idle or busy condition of said line, and means for interrupting said holding circuit at spaced intervals, said relay being connected and arranged at least partially to restore and then to reoperate each time said holding circuit is interrupted during an interval when said line is busy and to remain restored when said holding circuit is interrupted during an interval when said line is idle.
30. In a telephone system, a subscriber's line, a plurality of substations associated with said line, a manually operable generator at each of said substations, means comprising said generators for signaling between said substations on reverting calls, an automatic switch having access to said line, an alternating current relay operative in response to the operation of the generator at one of said substations, means responsive to the operation of said relay for marking said line as busy, thereby to prevent the seizure of said line by said automatic switch, a holding circuit for said relay, means responsive to the operation of said relay for completing said holding circuit and for maintaining said holding circuit completed independently of the idle or busy condition of said line, and means for momentarily interrupting said holding circuit at spaced intervals, said relay being connected and arranged at least partially to restore and then to reoperate each time said holding circuit is interrupted during an interval when said line is busy and to remain restored when said holding circuit is interrupted during an interval when said line is idle.
